(57) CLAIM

The ornamental design for a waste receptacle with bag dispenser, as shown and described.

DESCRIPTION

FIG. 1 is a rear elevation view of a waste receptacle with bag dispenser showing our new design;

FIG. 2 is a front elevation view thereof;

FIG. 3 is a left side elevation view thereof, the opposite side being a mirror image of the shown;

FIG. 4 is a top plan view thereof;

FIG. 5 is a bottom plan view thereof;

FIG. 6 is an isometric view thereof; and,

FIG. 7 is a cross-sectional view thereof taken along line 7-7 of FIG. 1.
